UNITED STATES PATENT OFFICE

2,553,304

VAPORIZING TYPE OIL BURNER

Herbert F. Daniels, Portland, Oreg.

Application April 26, 1948, Serial No. 23,170

2 Claims. (Cl. 158—91)

1

This invention relates generally to heat generating devices and particularly to an oil burner.

The main object of this invention is to produce a burner especially adapted for small installations and which can be easily constructed at a minimum cost for time and material by the use of castings.

The second object is to so construct the burner that the parts subjected to the most heat will receive the greatest cooling action.

A further object is to so construct the burner that expansion stresses will not be injurious to the burner.

The principle of operation is similar to the burner described in my United States application, Serial Number 769,452, filed August 19, 1947, over which the device described herein is an improvement.

I accomplish these and other objects in the manner set forth in the following specification, as illustrated in the accompanying drawing, in which:

Fig. 1 is a perspective view of the complete burner with parts broken away in section to disclose the construction.

Fig. 2 is a vertical section taken along the line 2—2 in Fig. 3.

Fig. 3 is a vertical section taken along the broken line 3—3 in Fig. 2.

Fig. 4 is a horizontal section taken along the line 4—4 in Fig. 3.

Fig. 5 is a perspective view of the adjusting frame.

Like numbers of reference refer to the same or similar parts throughout the several views.

Referring in detail to the drawing, there is shown an elongated horizontal air box consisting of the top 10, the bottom 11, the sides 12 and the connecting ends 13 and 14. This air box unit is cast from any desirable material and has formed in the rear end of the bottom 11 an air inlet opening 15 which is connected by the air duct 16 to the fan casing 17 within which is a fan (not shown) which is operated by a motor 18.

In the forward end of the bottom 11 are formed the air outlet orifices 19 and 20. The orifices 20 are pointed downwardly and outwardly.

Under the forward end of the bottom 11 is the vaporizing compartment 21 whose side walls 22 extend upwardly along the sides 12 and separated therefrom by a packing 23 and secured thereto by means of the screws 24.

Connecting the side walls 22 is a rear wall 25 which extends from the underside of the bottom 11 to the bottom 26 of the vaporizing compart-

2

ment 21. The forward end 27 of the bottom 26 slopes upwardly to the edge 28 of the burner orifice 29.

The front 30 is vertical and extends downwardly from the end 13 to the backwardly turned bottom 31 of the duct 32 whose side 33 is joined to the bottom 26.

The edge 28 is provided with air outlet orifices 34 which point upwardly and outwardly. Curved walls 35 are provided at each corner 36 and form ducts 37 which connect the air box 38 with the duct 32 through the opening 39 formed in the bottom 11.

Oil is admitted to the compartment 21 through an oil feed pipe 40 under the control of the float valve 41 which is automatically closed when the oil level exceeds a safe level. Such devices are in common use and require no explanation here.

In Fig. 5 is shown the frame 42 consisting of a rectangular member having the vertical sides 43 and the horizontal top 44 and bottom 45. The vertical sides 43 have their faces 46 angled with relation to the outer sides 47 while the front 48 is normal to the sides 47.

The top 44 has a horizontal upper face 49 which is normal to the front face 50. The rear face 51 is inclined with relation to the faces 49 and 50.

The bottom 45 of the frame 42 is somewhat wider than is the rest of the frame and has its underside 52 resting on the bottom 26 while its rear and front faces 53 and 54 are oppositely inclined, leaving a narrow rim 55 along its top edges which is somewhat shorter than the edge 56. The ends 57 of the bottom 45 are inclined as are the faces 53 and 54.

The frame 42 is free to move along the bottom 26, thereby determining the vaporizing area.

It will be seen from the foregoing that this arrangement makes possible the construction of a burner of a type by means of a casting process.

It will also be noted that air from the air box is pre-warmed before it escapes through the holes 19 and 20 and that the air which passes downwardly through the holes 39 and through the ducts 37 supplies the secondary air outlets 34 and 34A with super-heated air, and due to the fact that the duct 32 is fed from both ends, the air delivery is uniform along the length of the edge 28.

The purpose of the construction in Fig. 5 is to insure stability to a part which cannot well be otherwise secured and at the same time to provide the greatest amount of evaporating surface 55 for the oil as it passes over the edge 55. Although

enough clearance is provided to permit the frame 42 to be moved for adjustment, there is no objectionable by-passing of oil around the ends 47 as the clearance is soon taken up with residue and any oil which does find its way around the ends is vaporized and the gas itself acts as a barrier to the oil.

The purpose in making the frame 42 movable is to change the relative sizes of the vaporizing area between the frame 42 and the rear wall 25, and the mixing and combustion space between the frame 42 and the front 30.

I claim:

1. In a burner of the class described, the combination of a vaporizing chamber having a burner orifice at the upper portion of one end of the chamber, the bottom of said chamber being substantially horizontal at the end opposite said orifice, the remainder of said bottom sloping upwardly to the lower side of said orifice; an air manifold around said orifice having outlet holes discharging converging air streams into the flame coming from said orifice, adjustable means for controlling the effective area of the evaporating surface, means for supplying oil to said chamber and means for supplying primary air to the interior of the chamber and secondary air to said converging air streams.

2. In a burner of the class described, a combustion chamber consisting of a channel shaped box having a horizontal bottom extending from the middle of its length to one end thereof and having a rear wall at said end extending to the top of the side walls of the channel, the remainder of said bottom sloping upwardly to a

plane below the top of said rear wall, the front end of said chamber having an opening therein constituting a burner orifice, the front corners having air manifolds disposed therein extending downwardly from the top of said rear wall to the under side of said sloping bottom and along the under side thereof, along the width of the orifice, a movable frame mounted on the horizontal portion of said bottom for controlling the effective area of the evaporation surface, an air box extending over the top of said burner beyond its rear end, communicating with said manifold, and having air outlet openings in that portion of the air box directly above the sloping portion of said bottom.
